ATTORNEY.

UNITED STATES PATENT OFFICE

2,479,710

FLY-TYING BOBBIN

Ivan W. Arnold, North Hollywood, Calif.

Application April 14, 1947, Serial No. 741,363

3 Claims. (Cl. 242—140)

1

The present invention relates to fly-tying bobbins.

In the making of flies for fishing purposes, the flies are usually formed on the fish hook. To accomplish this, feathers of different colors are tied to the hook by means of thread. Usually the thread is wrapped around portions of the feathers and the hook, the final fly being of a form which is attractive to a fish, causing it to snap at the fly and thus engage the hook. The making of flies has become an art, requiring a means for rapidly forming the fly on the hook.

An object of the present invention is to provide a means whereby thread may be rapidly wrapped around the various feathers and the hook to form a fly, the operator at all times being able to observe his handicraft.

A further object of the invention is the provision of a device for tying flies which is easily manipulated, and which assures a better fly construction.

It has been found that use of the present invention increases an operator's speed in the forming of flies on a fish hook. It is not uncommon for an operator with fair skill using the present device to form thirty flies an hour.

A further object of the invention is a fly-tying bobbin which is simple of construction, easily loaded with thread, attractive in appearance, inexpensive in cost of manufacture, and superior to devices now known to the inventor.

In the drawing:

Figure 1 is a side view of the invention looking in the direction of the arrow 1 of Figure 2,

Figure 2 is an end view looking in the direction of the arrow 2 of Figure 1, and,

Figure 3 is a sectional view on an enlarged scale, taken on the line 3—3 of Figure 1.

Referring now to the drawing:

The fly-tying bobbin of the invention is designated as an entirety by the numeral 1, and includes a body 2, one portion 3 of which is of uniform external diameter, while an elongated concavely tapered portion 4 extends from said portion 3 to form an extension or nose portion. The portion 3 is provided with an enlarged bore 5 opening outwardly from one end of the body, as shown at 6; while the wall adjoining said bore 5 and inwardly of the body is concavely reduced in diameter, as shown at 7, to where it merges and communicates with an axial bore 8 in the extension or nose 4, and which bore 8 in turn communicates with a reduced diameter axial bore 9 extending to the tip 10 of the nose. The portion 3 is formed with axially aligned trans-

2

verse bores 11 and 12, bore 12 being of greater diameter than bore 11; portion 3 is bored inwardly at 13, and communicates with bore 11. The bore 13 is reduced in diameter at 14. Such reduction may be accomplished in any convenient manner, such as by peening the end of the body adjacent said bore where it communicates with the bore 11. Bore 13 is adapted to receive a ball 15, which projects within bore 11, said ball being urged to said position by a coiled spring 16 held within the bore 13 by a nut 17 in engagement with threads formed in the wall bounding the bore 13. A bobbin 18 extends between and is received in part within the bores 11 and 12.

15 The bobbin is of the usual spool type, having heads 19 and 20. The head 19 has a diameter slightly less than the internal diameter of bore 11, and said head is formed with an annular groove 21. The head 20 has two portions of different diameter, as shown at 22 and 23, the portion 22 fitting snugly within the bore 11, while the portion 23 engages the outer surface of the portion 3 and limits movement of the bobbin in one direction. The portion 3 is formed with a 20 transverse slot 24 extending from the end of said body to the bore 12.

The operation, uses and advantages of the invention just described are as follows:

25 The bobbin is wrapped with thread 25, whereupon the thread, with the bobbin exterior of the body, is passed through the bores 8 and 9. This may be accomplished by running a needle having a hook end through the said bores to contact the thread and draw the same through the said bores. After this is accomplished, the bobbin may be placed in the body by passing the head 19 first through bore 12 and then into bore 11, at which time the spring-pressed ball 15 will be received within the annular groove 21. The thread may then be passed through slot 24 so that upon pulling that portion thereof which extends through the tip 10, the thread will assume the position shown in Figure 3. The ball 15 exerts enough pressure against the head to permit easy rolling of the bobbin, and just sufficient friction to maintain a proper tension on the thread 25 when the thread is being used to form a fly. In other words, the spring-pressed ball acts as a friction means for the bobbin.

30 The operator, in the use of the invention, uses a suitable clamping means for holding the fish hook. He then takes the various objects which make up a fly, such as small feathers, and while holding them in one hand against the fish hook, rapidly wraps the thread about the hook and the

feathers, adding such other objects as may be necessary to form a complete fly. The long pointed nose of the device allows the operator to rapidly wrap the thread about the fly and the hook, and further permits a tying thereof when desired. Proper tension is maintained on the thread by maintaining a friction means for the bobbin. The use of this device assures that the fingers of the operator are not brought into contact with the impaling portion of the hook, with the result that the operator does not suffer any injury to his fingers while forming the fly. The long tapered nose permits the operator to watch the forming of the fly at all times, his vision not being obscured as would be the case if he utilized the fingers of both hands for wrapping and tying the thread about the hook and the fly.

I claim:

1. A device of the character disclosed, including a cylindrical body formed with an elongated conical extension, both the extension and said body formed with coaxial bores, said body provided with diametrically positioned transverse bores, a bobbin formed with head portions, the head portions adapted to be received within the transverse bores, and friction means for engagement with a head portion of the bobbin to impose a tension upon any thread carried by the bobbin and passed through and outwardly of the bores in said tapered extension.

2. A device of the character disclosed, including an annular body portion formed with an elongated tapered extension, the extension being provided with an axial bore communicating with the interior of the annular body; said annular body

5 formed with transverse bores, a bobbin diametrically spanning the annular body and received in said transverse bores, said bobbin having a head portion provided with an annular groove and said body provided with a spring-pressed ball for reception in the annular groove to thereby impose resistance to a turning of the bobbin.

3. A device of the character disclosed, including a body provided with an elongated tapered extension, said body and said extension being axially bored, the diameter of the bores in the extension being small in comparison to the diameter of the bore in the body; said body being 10 transversely bored; a bobbin having head portions for reception within said transverse bores, said body formed with a transverse slot extending from the end of said body to one of said transverse bores, said transverse slot permitting any thread on the bobbin to be passed within the body.
